BOAT

Marcel Raveau, Lindenhurst, N. Y.

Application February 24, 1948, Serial No. 10,439

3 Claims. (Cl. 9—6)

1

This invention relates to new and useful improvements in a boat.

An object of the present invention is to provide a boat of the semi-round bottom outboard motor type, the bottom of which is formed of double layer material and the sides of which are formed of a single layer of material such as plywood or resinous plastic material which ordinarily cannot be bent about two axes normal to each other.

Another object is to provide a boat of the aforesaid type having spaced specially disposed bulges in its bottom, the bulges being formed by specially shaped chines.

A further object is to provide a boat as aforesaid in which the bulges are effected by forcing a compound curve in the flat sheet of plywood.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a boat constructed in accordance with the present invention.

Fig. 2 is a rear view of the boat.

Fig. 3 is an inverted view of the boat, taken from the rear, in perspective.

Fig. 4 is a side view of the boat.

Fig. 5 is an inverted view of the frame of the boat, taken from the prow, in perspective.

Fig. 6 is an inverted view of the frame of the boat in side elevation.

Fig. 7 is a view, taken on the line 7—7 of Fig. 6, with the longitudinal frame pieces omitted.

Fig. 8 is an outside view of a chine.

Fig. 9 is a view of the right end of the chine.

Fig. 10 is a view of the left end of the chine.

Fig. 11 is an side view of the chine.

Fig. 12 is a plan view of superimposed sheets of plywood marked for cutting to form the bottom and portions of the sides of the boat.

Fig. 13 is a view of a sheet of plywood from which the remainder of the sides is made.

Fig. 14 is a partial enlarged sectional view of the completed boat taken on the line 14—14 of Fig. 3.

The frame 10 of the boat 11, constructed in accordance with this invention, may be best viewed in Fig. 5. It consists of a stern transom 12, preferably of one piece of oak or other suitable wood. A keelson 13 is grooved in the center

2

of the bottom edge of the stern 12 and is jointed to a stem piece 14 which forms the prow of the boat. The stem piece is triangular in cross section with its base forming a continuation of the top or inner face of the keelson. The keelson is flat but the stem piece curves forwardly and upwardly to define the height of the prow of the boat.

The boat has three ribs of general U-shape.

10 The forward rib 15 closest to the stem piece is narrow and deeply curved; the intermediate rib 16 is wider and shallower; and the rear rib 17 is wider still. Each rib is formed of a bottom piece and two side pieces connected thereto. For example, reference may be had to rib 17 shown in Fig. 7. It consists of a bottom piece 17a and side pieces 17b. The bottom piece 17a is curved and the side pieces are straight and converge upwardly and inwardly. Each side piece is mortised to its end of the bottom piece and the joint is reinforced by a cover cleat 18. The connections may be made with waterproof glue such as weldwood glue and reinforced with copper or brass nails or rivets or screws as desired.

20 Ribs 15 and 16 are of conventional construction and have center grooves for the passage therethrough of the keelson in the usual manner. Rib 17 has a similar groove indicated at 19 in Fig. 7. The ribs, stem piece and stern are connected by two gunwales 20, the ribs having grooves 21, see Fig. 7, for the gunwales and the stern 12 having similar grooves. The two gunwales meet nicely at the stem piece in a tapered point. Beneath the gunwales are longitudinal chines 22 which are connected similar to the gunwales. The chines are best shown as raw stock in Figs. 8 and 11. Each chine may be described as having a base 23, rectangular in cross section, a little more than half of the rear end portion thereof also having a triangular portion 24 superposed integrally on the base. Thus it differs from a conventional chine which usually has only four sides, one of which may be inclined. The instant chine at its forward end has an

45 inner side 25, an outer side 26 and connecting edges 27 and 28. At its rear end it has the inner side 25 and edges 27 and 28. It also has the angular outer faces 29 and 30 adjacent edges 27 and 28 respectively. Furthermore, this five 50 sided part of the chine is wider than the four sided part and the two parts are connected by a taper 31.

The chines run along the sides of the boat starting at the bottom corners of the stern and ending nearly at the top of the stem piece, as can

be seen from the inverted view of Fig. 5. They are set in grooves in the ribs and stern. The rib grooves are at the joints of the bottom and side pieces and in the reinforcing cleats. This can be seen, for example, in Fig. 7, wherein the chine groove 32 is cut in the cleat 18 and also runs through the overlapping portions of the bottom and side pieces of the ribs. The overlap is indicated in the dotted lines in Fig. 7.

As thus far described, the frame is more or less conventional except for the specific shape of the chines. It may be made by well known conventional rules of small boat construction, such as, for example, making the stem piece of laminations, that is, of plywood.

The frame further includes, as integral parts of the bottom piece 17a of the rib 17, two depending bulges 33. The normal line of the rib is indicated in dot-dash lines in Fig. 7. The bulges 33 are each a convex extension, tapering into the rib bottom piece at its ends and being extended the farthest at its center. There is a bulge 33 on each side of the keelson. Each bulge includes a groove 34 at its deepest or center point. The frame further includes two longitudinal short ribs 35. Each rib 35 is grooved into the stern 12 at its rear end, fits in its correlated groove 34 in its bulge 33 and is grooved into the rib 16. It does not extend beyond the rib 16 and rib 16 is normal, that is, it has no bulge.

The importance of the bulges 33 can best be seen by viewing Fig. 5, wherein it will be seen that the rear end of each rib 35 is in the normal curve line between the keelson 13 and the chine 22, and this is also true of its forward end. At its center, however, it is forced below the normal curve line by the adjacent bulge 33.

The frame is covered by flat plywood or resinous plastic material. Superimposed sheets of material 36, see Fig. 12, are cut along the lines 37 and 38 and separately shaped and then placed on the keelson and attached thereto as by gluing and riveting. The lines 37 and 38 follow the stem piece and form the prow. The outer edges 39 overlap the chines and are fastened thereto. One-half of the chine is covered. For example, referring to Fig. 8, the face 30 and one-half of the rectangular portion face 26 is covered. The face 29 of the chine and the remainder of the face 26 is covered by the side pieces which are the plywood or resinous plastic material sheets such as the sheet 49 of Fig. 13. The sheets 36 and 40 meet at the juncture of faces 29 and 30 with the bottom of the sheet 40 overlapping the sides of the sheets 36, as shown in Fig. 14. Thus it will be seen that the sheets 36 form the entire bottom and a portion of each side up to the chines.

The sheets 36, since they cover the entire bottom, provide a perfectly smooth egg-like surface which is excellent for planing, see Fig. 3. The sheets 36 are securely fastened to the keelson, ribs, stern, chines and stem piece. The sheets are very securely fastened to the ribs 35 after being individually bent around two axes to form two bulges 41, each of which is like a longitudinal section, less than half, of a football, see Fig. 3, where the bulges are indicated in dotted lines, and see Fig. 4, where the depending of the bulges 41 is clearly visible.

The boat has no keel, but has two spaced runners 42 which are the same length as the ribs 35 and are fastened thereto, the runners 42 following the curve of the bulges 41. These runners provide a safety feature during planing and turning and protect the bottom of the boat much in

the same fashion as a keel protects the bottom of most outboard boats. The remainder of the boat is finished, seated and decked in the usual manner.

5 The position of the bulges is important. They are about half way between the stern 12 and the center of the boat. This is the part of the boat that remains in contact with the water, especially at high speeds. Even at high speeds the boat will 10 not slap up and down, or "porpoise" as it is commonly called, the bulges preventing this and keeping the boat substantially level regardless of speed.

While the construction of the boat has been described re the use of flat plywood, it may be made of other material if desired, such as plastic which is now finding common usage in boat construction. Since the prow and bottom are of two pieces of plywood, a strong plywood having a 20 thickness of $\frac{1}{4}$ or $\frac{5}{16}$ of an inch is chosen so that when the bottoms are combined the finished bottom will be $\frac{1}{2}$ or $\frac{3}{8}$ inch thick giving the finished bottom the correct strength for supporting weight and for resisting blows such as hitting rocks head 25 on or dragging over rocks. The sides above the side portions provided by the bottom can be lighter plywood. That is, sheet 40 can be a single sheet of $\frac{1}{8}$ or $\frac{1}{4}$ inch plywood.

Forming the bottom of the boat of superimposed layers of material produces a boat having an extremely strong bottom, and yet the layers can be individually shaped making it easier to shape the bottom portion than if the bottom were 35 formed of a single layer of material having the same thickness as the combined layers.

If the bottom had only one bulge in the center then when the boat made a turn and banked, half of the bulge would be ineffective. In the instant boat, regardless of the degree of banking, one bulge is fully under water. This is important in racing a close course around buoys. The seam batten inside and the fins or skegs outside help to give a flowing curve to the bulges. The two bulges on the bottom give a lift to the boat without forming any water or air disturbance directly in the front of the propeller of the outboard motor, not shown, which is very important on fast boats as the propeller is able to thus get a continuous stream of water. Boats equipped with these bulges are able to carry a heavy load with very little loss of speed.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a boat having a stern transom and a pair of spaced transverse ribs forward of the transom and extended parallel thereto, a keelson connecting the transom and the ribs along the longitudinal center of the boat, one of the transverse ribs being located substantially midway between the transom and the other rib and having depending bulges on opposite sides of the keelson and spaced therefrom, short ribs extending longitudinally on opposite sides of the keelson from the transom and across the one rib to the other rib, said short ribs being bulged intermediate of their ends downward over the bulges 70 of the one rib, a sheet covering the bottom of

the boat, said sheet being bulged downwardly convexly over the bulges of said short ribs.

2. In a boat having a stern transom and a pair of spaced transverse ribs forward of the transom and extended parallel thereto, a keelson connecting the transom and the ribs along the longitudinal center of the boat, one of the transverse ribs being located substantially midway between the transom and the other rib and having depending bulges on opposite sides of the keelson and spaced therefrom, short ribs extending longitudinally on opposite sides of the keelson from the transom and across the one rib to the other rib, said short ribs being bulged intermediate of their ends downward over the bulges of the one rib, a sheet covering the bottom of the boat, said sheet being bulged downwardly convexly over the bulges of said short ribs, and runners secured to the outer face of said sheet parallel to and coextensive with said short ribs.

3. In a boat having a stern transom and a pair of spaced transverse ribs forward of the transom and extended parallel thereto, a keelson connecting the transom and the ribs along the longitudinal center of the boat, one of the transverse ribs being located substantially midway between the transom and the other rib and having depending bulges on opposite sides of the keelson and spaced therefrom, short ribs extending longitudinally on opposite sides of the keel-

son from the transom and across the one rib to the other rib, said short ribs being bulged intermediate of their ends downward over the bulges of the one rib, a sheet covering the bottom of the boat, said sheet being bulged downwardly convexly over the bulges of said short ribs, and runners secured to the outer face of said sheet parallel to and coextensive with said short ribs, said runners being bulged downward over the downwardly bulged areas of said sheet.
